UNITED STATES PATENT OFFICE

ALBERT I. CILISKE, OF CHICAGO, ILLINOIS

COMBINATION TOOL

Application filed January 5, 1927. Serial No. 159,201.

This invention relates to certain novel improvements in combination tools and more particularly to a combined journal gage and caliper and has for its principal object the provision of an improved construction of this character which will be highly efficient in use and economical in manufacture.

When railroad car wheels and axles are changed under cars of ownership foreign to the company making these changes a wheel and axle statement must be furnished the car owners as required by the code of rules "M. C. B." governing the condition of and repairs to freight and passenger cars for the interchange of traffic adopted by the American Railway Association—Mechanical Division.

The information or rather the data that must be shown on this statement includes among other things the actual journal length dimension, the actual journal diameter dimension, the actual wheel seat diameter dimension, and the actual axle center diameter dimension.

The actual journal length dimension is at present procured with the aid of an ordinary rule of sufficient length and proper graduations. This rule is laid upon the journal and dimensions taken therefrom by the naked eye. This method of procuring this dimension is found to be unsatisfactory due to the difficulty encountered in having the rule rest at the proper point at the back end of the journal and making the necessary allowance for the journal collars worn unevenly.

The journal diameter dimension, wheel seat, and axle center diameters at present are procured with the aid of an ordinary caliper independently of the rule together with the use of a rule. These dimensions are likewise procured in an inadequate manner and inasmuch as it is an essential element to procure the positive accurate dimensions it is an object of this invention to provide a combination tool for the purpose and which tool will give instantaneous and accurate dimension readings.

Other objects will appear hereinafter.

The invention consists in the novel combi-

nation and arrangement of parts to be hereinafter described and claimed.

The invention will be best understood by reference to the accompanying drawings, showing the preferred form of construction and in which:

Fig. 1 is a top edge view of the invention;

Fig. 2 is a side elevational view of the invention showing the same in extended position;

Fig. 3 is a side elevational view of the invention similar to that shown in Fig. 2 and illustrating the invention in applied position for gaging the journal length;

Fig. 4 is a side elevational view of the invention showing the same in folded position;

Fig. 5 is a sectional detailed view of the same taken substantially on line 5—5 of Fig. 4;

Fig. 6 is a side elevational view of the invention showing the caliper legs thereof in position for gaging the journal diameter;

Fig. 7 is a fragmentary and side view of the invention showing the same in position for gaging the back journal fillet;

Fig. 8 is a fragmentary and side elevational view showing the invention in position for gaging the journal collar;

Fig. 9 is a sectional detailed view taken substantially on line 9—9 of Fig. 6; and

Fig. 10 is a sectional detail view taken substantially on line 10—10 of Fig. 6.

Referring to the drawings, the invention includes two rule members 11 and 12 pivotally connected together through the medium of a pintle 13 whereby the rule members may be expeditiously folded upon each other.

Pivotal movement of the rule members to substantially aligned position with respect to each other is guided by means of a lip 14 formed on the rule member 11 and adapted to flatly engage the top edge of the rule member 12. The rule members 11 and 12 have rounded corners 15 defined by different radii and these rounded corners are selectively adapted for journal fillet gaging.

The lower edges 16 of the rule members have formed, a predetermined distance inwardly from their end edges 17, notches 18 of different dimensions. These notches 18

are selectively adapted for journal collar gaging.

The rule member 11 has formed thereon, inwardly of the notch 18 thereof, a finger 19. This finger 19 has a curved edge 20 for engagement with the surface of the back journal fillet and also functions to properly position the tool upon the journal for measuring the length thereof.

Formed in the rule member 11 is an elongated slot 21. Carried by the rule member 11 for slideable movement longitudinally thereof is a carriage plate 22 which has an upper angled end portion 23 slidably engaging the top edge 24 of the rule member 11. Secured to this carriage plate for positioning upon the side of the rule member 11 opposite the carriage plate is a caliper leg 25. This caliper leg is secured to the carriage plate for pivotal movement relatively of the rule member 11 through the medium of a pindle 26 which has its shank portion extending through the slot 21. When the carriage plate is positioned in its extreme position inwardly upon the rule member 11 the caliper leg, when pivoted downwardly is limited to taking a true position substantially at right angles to the rule member 11 through the medium of a lateral stop member 27 formed on the rule member 11.

Formed in the rule member 12 is an elongated slot 28. Slidably carried by this rule member 12 is a carriage plate 29 which has a lateral lip 30 slidably engaging the top edge 31 of the rule member 12. Secured to the carriage plate, through the medium of a pindle 32 which has its shank portion working in the slot 28, for positioning on the side of the rule member 12 opposite the carriage plate, is a caliper leg 33 which cooperates with the caliper leg 25 for journal diameter gaging. This caliper leg is likewise limited to a position substantially at right angles with respect to the rule member 12 through the medium of a lateral stop 34 formed on the carriage plate 29.

Referring to Fig. 3 the journal of an axle is indicated generally at 11'. This journal includes a collar 12' and a back fillet 13'.

My improved combination tool is especially and selectively designed for gaging the different measurements required as among other data for the wheel and axle statement herein referred to, and this is accomplished in the following manner. To measure the journal length the rule members, which have graduations 35 formed thereon, are extended in aligned position with respect to each other in such position being facilitated by cooperation of the lip 14. The tool is placed upon the journal with the edge 20 of finger 19 engaging in the fillet 13'. The carriage plate is moved inwardly of the rule member 12 and also inwardly of the collar 12' to permit positioning of the lower edge of the rule member

12 upon the edge of the collar 12'. After this is accomplished the gage is moved outwardly upon the rule member 12 until its gage lip 15' engages the inner surface 14' of the collar 12'. The tool in such position can be expeditiously read and accurate dimension taken therefrom.

When gaging the journal diameter the caliper legs are pivoted into position substantially at right angles with respect to the rule members, said caliper legs being limited in such movement through the medium of the lateral stop members 27 and 34. The caliper upper angled end portion 23 is positioned to engage approximately the center of the journal. The caliper leg 33 is now moved longitudinally of the rule member 12 to likewise engage the center of the journal. The tool in this position can likewise be expeditiously read and actual dimension taken therefrom.

The curved corners 15, are designed by different radii to permit gaging the back fillets of journals of different dimensions and this gaging is accomplished in a manner best understood by reference to Fig. 7.

The notches as herein indicated are especially designed for gaging the journal collar thickness and this gaging may be best understood by reference to Fig. 8.

By the use of a tool constructed in accordance with the description herein set forth it will be seen that by combining the caliper gage and rule in one tool these tools will at all times be convenient for use and will save considerable time because it is not possible to loose either one of the tools independently of the other. Again it will be manifest that my improved tool greatly facilitates accurate dimensioning of a journal and can be expeditiously used by others than those skilled in the art.

The tool may be formed of any approved material as will best serve the purpose. The tool enables one to procure accurate diameters and lengths and eliminates the possibilities of procuring inaccurate dimensions by not having a rule as well as a caliper and also the tool, by its selective construction can be properly positioned upon the journal for caliper or rule gaging use.

As shown in Figs. 2 and 3 and 6 the rule members have formed along their upper edges graduations indicated by their respective numbers 36'. When the caliper legs are positioned in the position illustrated in Fig. 6 these numbered graduations 36' facilitate accurate reading of the dimensions between points of the caliper legs. This reading is procured by observing the position of the edges 37' of the carriage plates 22 and 29.

While I have illustrated and described the preferred form of construction for carrying my invention into effect, this is capable of variation and modification, without departing from the spirit of the invention. I, there-

fore, do not wish to be limited to the precise details of construction set forth, but desire to avail myself of such variations and modifications as come within the scope of the appended claims.

Having thus described my invention what I claim as new and desire to protect by Letters Patent is:

1. In a combination tool, two rule members pivotally connected together for folding upon themselves, means for limiting pivotal movement of the rule members for positioning the rule members in substantial alignment with respect to each other, said rule members having corresponding corners curved for journal fillet gaging and having notches formed in opposite end portions for journal collar gaging, a lateral finger formed on one of the rule members and having a curved edge for journal fillet gaging, a pair of cooperating caliper legs, means pivotally connecting the caliper legs to the rule members, and means limiting the pivotal movement of the caliper legs relative to the rule members and positioning the caliper legs substantially at right angles with respect to the rule members.

2. In a combination tool, two rule members pivotally connected together for folding upon themselves, means for limiting pivotal movement of the rule members for positioning the rule members in substantial alignment with respect to each other, said rule members having corresponding corners curved for journal fillet gaging and having notches formed in opposite end portions for journal collar gaging, a lateral finger formed on one of the rule members and having a curved edge for journal fillet gaging, a pair of cooperating caliper legs, means pivotally and slidably connecting the caliper legs to the rule members, and means limiting the pivotal movement of the caliper legs relative to the rule members and positioning the caliper legs substantially at right angles with respect to the rule members.

3. In a combination tool, two rule members pivotally connected together for folding upon themselves, means for limiting pivotal movement of the rule members for positioning the rule members in substantial alignment with respect to each other, said rule members having slots formed therein, carriage plates disposed on one side of each of said rule members but on opposite sides thereof caliper legs, and means extended through said slots and secured to said carriage plates for securing said caliper legs for disposition opposite said carriage plates and for pivotal movement with respect to said rule members.

In testimony whereof I affix my signature.
ALBERT I. CILISKE.
